FOOTWEAR HEEL FASTENER

Filed Feb. 12, 1940

UNITED STATES PATENT OFFICE

2,224,476

FOOTWEAR HEEL FASTENER

Julius Farina, Springfield, Mass.

Application February 12, 1940, Serial No. 318,622

4 Claims. (Cl. 36—42)

The invention relates to footwear heel fasteners and more particularly to refinements to the subject matter of United States Letters Patent No. 2,140,422, issued December 13, 1938.

5 The primary object of the invention is the provision of a device or fastener of this character wherein the heel to a shoe can be conveniently and easily fastened and in the fastening thereof it may be adjusted with respect to 10 the heel portion of the sole of said shoe for effecting the final securing thereof in its proper place, the device or fastener constituting the present invention is a refinement over the subject matter of United States Letters Patent No. 2,140,422 15 issued December 13, 1938.

Another object of the invention is the provision of a device or fastener of this character wherein the screw for securing the heel of a shoe in place is protected in that the material from 20 which the heel is made, as it is preferable to have the heel constructed from composite, plastic material and molded, will not make contact with the said screw or in any manner interfere therewith when used for the securing of the heel to the shoe sole at its heel end, thus allowing the 25 convenient securing of the heel in place.

A further object of the invention is the provision of a device or fastener of this character wherein there is involved a screw and a nut, these 30 being interfitted for the coupling or securing of the heel to a shoe at the heel end of the latter and allowing for the easy removal of the heel should it become damaged or unfit for service or use so that a substitute heel can replace the same 35 without requiring the possessor of the shoe seeking a cobbler or other artificer for the replacement of the discarded heel in that an ordinary screw driver is the only tool required for the fastening or detachment of the heel when the 40 occasion demands.

A still further object of the invention is the provision of a device or fastener of this character, which is simple in its construction, thoroughly reliable and efficient in operation, easy 45 of manipulation, enabling the substitution of one heel for another and the application to a shoe sole, the proper adjustment thereof for the required location of such heel on finally securing the same to the shoe and economical in manufacture.

With these and other objects in view, the invention consists in the features of construction, combination and arrangement of parts as will be hereinafter more fully described in detail, illustrated in the accompanying drawing, which dis-

closes the preferred embodiment of the invention and pointed out in the claims hereunto appended.

In the accompanying drawing:

Figure 1 is a fragmentary vertical longitudinal sectional view through the heel area of a shoe 5 and a heel therefor showing the fastener or device constructed in accordance with the invention securing the heel to the shoe.

Figure 2 is a perspective view of an adjunct of the device or fastener. 10

Figure 3 is a top plan view thereof partly broken away.

Figure 4 is a perspective view of the nut companion to the screw of the device or fastener.

Figure 5 is a plan view of a cap for association 15 with the screw.

Figure 6 is a top plan view of the head of the screw.

Figure 7 is a fragmentary vertical longitudinal sectional view through the screw. 20

Similar reference characters indicate corresponding parts throughout the several views in the drawing.

Referring to the drawing in detail, A designates generally the heel portion of a shoe, which, as usual, comprises an outsole 10, an insole 11 and a heel, a portion of the latter being indicated at 12, respectively. This heel 12 is adapted for detachable fastening to the outer face of the outsole 10 by the device or fastener constituting the 25 present invention and hereinafter fully described. 30

The device or fastener comprises a screw 13 having a head 14 of partial spherical formation for loose engagement and seating in a central socket 15 therefor of a cap 16. The socket 15 is 35 created in the cap 16 by a central outtruck apertured portion 17 thereof. The cap 16 is countersunk in the insole 11 at the proper location and also the portion 17 is partially countersunk in the outsole 10 while the screw 13 has its 40 threaded shank passed through suitable clearances therefor, as at 18, one being provided at the countersink for the portion 17 in the insole 11 and the other being provided in the outsole 10. 45

Adapted to be embedded in the heel 12, which is of the molded type made from plastic composition, is a two-part housing, which parts 19 and 20 thereof are separably interfitted with each other at the formations 21 and 22, respectively. These formations 21 and 22 create a slideway for 50 a nut 23 adapted for threaded connection with the screw 13. These sections including the formations 21 and 22 of the housing conceal and confine the screw 13 and the nut 23 when engaged with each other to eliminate any possi- 55

bility of the plastic material when being molded for the formation of the heel 12 from creeping into the said housing and making contact with the screw and nut or in any manner interfering therewith which would make it difficult for adjustment of the heel 12 and the fastening thereof onto the outsole 10 of the shoe as is clearly disclosed in Figure 1 of the drawing.

The section 19 of the housing is formed with a double-armed bail 24 depending from this section and retaining the section 20 in register with the said section 19 for assuring the interfitting of these sections with each other and maintaining this interfitted relationship when the housing is embedded in the plastic substance when soft and at the time of the molding of such material for the formation of the heel 12. Due to the shape of the sections 19 and 20 with their formations 21 and 22 the heel 12 having the housing embedded therein is permitted to be adjusted in that the nut 23 is susceptible of sliding movement in the formations 21 and 22 while the sections 19 and 20 assure increased space for accommodation of the screw 13.

25 The head 14 is slotted at 25 for accommodating an ordinary screw driver or a screw driver-like key for the convenient turning of the screw 13 when in threaded engagement in the nut 23 and in this manner the heel 14 can be separably 30 coupled or secured in place at the heel area of the shoe or fastened tightly against the outsole 10 at the said end area of the shoe. The head 14 of the screw 13 is countersunk in the portion 35 17 of the cap 16, being within the socket 15 in said portion 17 of this cap when the heel has been secured to the shoe so that no discomfort to the wearer will occur in the use of the shoe.

The structure hereinbefore set forth and disclosed or illustrated in the drawing constitutes 40 refinement in the subject matter of United States Letters Patent No. 2,140,422, issued December 13, 1938.

The heel 12 is susceptible of forward and backward movement to an extent greater than side- 45 wise movements thereof and this simplifies the fastening of the heel 12 to the shoe.

The housing with the nut loose therein becomes a permanent part of the heel at the time the same is molded and thus heels so equipped 50 can be interchanged in their use for the fastening of the same to a shoe and this satisfies the requirements of the use of differently colored heels with a single shoe or the substitution of one heel for another, particularly where a heel 55 becomes unfit for use or damaged and the substitution can be made without requiring the services of a cobbler or other artificer, which would be the case if nails or the like were employed for the fastening of the heel to the shoe.

60 The device or fastener assures a firm and secure placement of the heel upon the shoe and the ready and easy separation with dispatch of the said heel from the shoe when the occasion requires in that a conventional screw driver or 65 the like is the only tool necessary for the fastening or unfastening of the heel to or from the shoe.

The bail 24 in its association with the sections of the housing assures a positive anchorage of the latter in the heel 12 and unitary therewith.

What is claimed is:

1. In a shoe, the combination of a sole provided in the heel area thereof with an aperture extending therethrough, a cap counterseated in the heel area and having a countersunk socketed portion, a heel fitting said heel area of the said sole and having a housing embedded therein, a slideway formation in said housing, a nut loosely fitted in said slideway formation, and a bolt in threaded engagement with said nut and having a head seated in the countersunk portion of the said cap for fixing the heel to the heel area of 15 said sole.

2. In a shoe, the combination of a sole provided in the heel area thereof with an aperture extending therethrough, a cap counterseated in the heel area and having a countersunk socketed portion, a heel fitting said heel area of the said sole and having a housing embedded therein, a slideway formation in said housing, a nut loosely fitted in said slideway formation, a bolt in threaded engagement with said nut and having a head seated in the countersunk portion of the 20 said cap for fixing the heel to the heel area of said sole, the said housing having interfitting separable sections, and a guide bail on one section for the other section of said housing. 30

3. In a shoe, the combination of a sole provided in the heel area thereof with an aperture extending therethrough, a cap counterseated in the heel area and having a countersunk socketed portion, a heel fitting said heel area of the said sole and having a housing embedded therein, a slideway formation in said housing, a nut loosely fitted in said slideway formation, a bolt in threaded engagement with said nut and having a head seated in the countersunk portion of the 35 said cap for fixing the heel to the heel area of said sole, the said housing having interfitting separable sections, and a guide bail on one section for the other section of said housing, the 40 said nut being of a size for free movement thereof in the slideway formation of the housing. 45

4. In a shoe, the combination of a sole provided in the heel area thereof with an aperture extending therethrough, a cap counterseated in the heel area and having a countersunk socketed portion, a heel fitting said heel area of the said sole and having a housing embedded therein, a slideway formation in said housing, a nut loosely fitted in said slideway formation, a bolt in threaded engagement with said nut and having a head seated in the countersunk portion of the 50 said cap for fixing the heel to the heel area of said sole, the said housing having interfitting separable sections, and a guide bail on one section for the other section of said housing, the 55 said nut being of a size for free movement thereof in the slideway formation of the housing, the said housing and slideway formations thereof being adapted to confine and conceal the said nut and screw when engaged with each other 60 for the fastening of the heel to the sole. 65

JULIUS FARINA.
